UNITED STATES PATENT OFFICE.

THOMAS A. VERHOEVEN, OF BUFFALO, NEW YORK, ASSIGNOR TO MERGENTHALER LINOTYPE COMPANY, A CORPORATION OF NEW YORK.

TYPOGRAPHICAL MACHINE.

1,099,476.

Specification of Letters Patent. Patented June 9, 1914.

Application filed February 6, 1913. Serial No. 746,495.

To all whom it may concern:

Be it known that I, THOMAS A. VERHOEVEN, a citizen of the United States, residing at Buffalo, in the county of Erie and State of New York, have invented certain new and useful Improvements in Typographical Machines, of which the following is a specification, reference being had therein to the accompanying drawing.

10 My invention relates to typographical machines, such as linotype machines of the general organization set forth in U. S. Letters Patents to O. Mergenthaler, Nos. 436,531 and 436,532, wherein circulating matrices 15 are released from a magazine or magazines in the order in which their characters are to appear in print and then assembled in line, the composed line transferred to the face of the slotted mold, the mold filled with 20 molten metal to form a slug or linotype against the matrices which produce the type characters thereon, and the matrices thereafter elevated and returned through a distributing mechanism to the magazine or 25 magazines from which they started. In such machines, the composed line of matrices is presented to the casting mechanism by a carrier, ordinarily known as the "first elevator", the presenting movement of which 30 may be varied in order to bring the line into appropriate relation to the mold, and thus to permit the employment of different matrices or molds of different size as may be necessary. For instance, in the use of 35 large matrices for head letters, it is customary to present the elevator at a different level from that at which it is presented with ordinary matrices, in order to insure the correct alinement of the characters thereon 40 with the mold slot. Such machines are also provided with means whereby the trimming knives may be adjusted to slugs or linotypes of different thickness as produced by different widths of the mold slot.

45 It is one of the purposes of my invention to effect the actuation of the means for arresting the first elevator in a different position simultaneously with the adjustment of the trimming knives, so that for any given 50 thickness of slug, the proper position of the elevator and the proper separation of the knives will be secured by a single operation. In this manner, I obviate the necessity for special attention or care on the part of the 55 operator, and also avoid the liability to imperfect results which arises in the event that

the devices are not correspondingly adjusted.

In the accompanying drawing, I have shown my improvement by way of example 60 and in preferred form, and as applied to the specific kind of machine already mentioned, but obviously many changes and variations may be made therein, and similarly it may be used in connection with other forms of 65 typographical casting machines, without departure from its spirit; and generally speaking, I desire it to be understood that I do not limit myself to any specific form or embodiment, except in so far as such limitations are specified in the claims.

Referring to the drawing: Figure 1 is a front perspective view of a portion of the casting mechanism of a linotype machine, having my invention applied thereto; and 75 Fig. 2 is a transverse vertical section, showing the parts in position for casting.

In most respects, the illustrated mechanisms are or may be substantially the same as those disclosed in the previously mentioned Letters Patent, or as employed in the commercial linotype machine. The rotatable mold wheel A is provided with one or more molds a, into which the molten metal is delivered from a melting pot (not shown). 80 The matrices X are supported in the first elevator B and are thereby presented to the mold. The extent of movement of the elevator is governed by the contact with the vise cap C of the stop screw D carried by 85 the elevator; and the rod E, ordinarily termed the "automatic", which controls the clutch mechanism, is actuated by the screw D¹ also carried by the elevator, the depression of the rod E being necessary to permit 90 the casting operation, when the elevator has reached its proper position.

In ordinary circumstances, such as in connection with matrices of ordinary font, wherein the characters are for example "14-point" or less, the elevator B descends until the stop screw D contacts directly with the vise cap C, and the screw D¹ with the rod E. If it is desired to use larger matrices, for instance for "head letters", say, from 14-point to 32-point or more, a stop member or piece F is employed which may be interposed at will between the screw D and the cap C, which relations are shown in Fig. 2. As previously stated, when the elevator descends to its full extent, the screw D¹ actuates the clutch rod E; but when the ele-

vator is arrested at a higher point, the screw would not contact with the rod, unless additional means were availed of. To this end the stop member F is provided with a pivoted finger or interponent F¹, which will be inserted between the rod E and the screw D¹, when the member F is brought into position to be engaged by the screw D, and thus effect the proper actuation of the clutch rod, even though the elevator be arrested at a higher point. Substantially similar devices are disclosed in Letters Patent to J. R. Rogers No. 890,177, except that therein the stop and pivoted interponent are adjusted by devices contacting with the keeper plate.

Referring to Fig. 1, I have illustrated the means whereby the knives may be adjusted to correspond to slugs of different thickness. This is effected by the movement of a handle H, connected to a rotary sector plate J provided with a series of studs J¹ of different height, whereby the trimming blades may be properly adjusted. The handle H is formed with a pointer H¹, which moves in relation to the point scale H², thus permitting the setting of the knives to any size desired. Further detailed description of these adjusting means may be found in U. S. Letters Patent to D. S. Kennedy 1,002,281.

Turning now to my improvement, it will be seen that the sector plate J has on its edge adjustable studs K, located and arranged to contact with one end of the pivoted lever L, engaging a second pivoted lever M, which is in turn connected to the pivoted extension N of the stop member F. The studs K are located in such position that they will engage and operate the lever L, when the handle H has been moved to adjust the trimming knives for ordinary slugs, in one case, and for slugs bearing much larger characters, in another case. Thus, in Fig. 1 the handle H is shown with its pointer H¹ standing opposite point 36 on the scale H², the movement of the handle to this position causing the corresponding stud K to operate the lever L, to bring the stop member F into its operative or arresting position. If now the handle is moved in the opposite direction so as to locate its pointer opposite or below point 36 on the scale, the other stud K will operate the lever L to withdraw the stop member F from its operative position, so as to permit the elevator to descend to its full extent. It will be obvious of course that the studs may be located in different positions on the sector plate J, so as to act upon the lever L for different adjustments of the trimming knives.

As previously stated, my invention may be carried into effect by other forms of devices, which may vary widely from that shown in

the present instance, both in construction and operation, and still be comprised within its scope. Such devices will readily suggest themselves to persons skilled in the art.

Having thus described my invention, its construction and mode of operation, what I claim and desire to secure by Letters Patent of the United States is, as follows:

1. In a typographical machine, the combination of a mold, a matrix carrier movable to different positions in relation thereto, knife adjusting mechanism, and connections therefrom to establish correspondence between the adjustment of the knives and the position of the carrier.

2. In a typographical machine, the combination of a mold, a matrix carrier movable to different positions in relation thereto, means for controlling the position of the carrier, knife adjusting mechanism, and connections between the said adjusting mechanism and the said controlling means.

3. In a typographical machine, the combination of a mold, a matrix carrier movable to different positions in relation thereto, knife adjusting means, and devices actuated by said knife adjusting means for controlling the position of the carrier.

4. In a typographical machine, the combination of a movable matrix carrier, an adjustable stop device to arrest the movement of said carrier, knife adjusting mechanism, and connections between the stop device and knife adjusting mechanism to effect their simultaneous adjustment.

5. In a typographical machine, the combination of a mold, a matrix carrier movable to different casting positions in relation to the mold, a stop device to arrest the carrier in one of said positions and movable into and out of operative position, adjustable parts mounted independently of the carrier, and connections whereby the adjustment of said parts simultaneously effects the movement of said stop device into or out of operative position as required.

6. In a typographical casting machine comprising matrices, the combination of a mold, means whereby the matrices and the mold may be brought into different casting positions with relation to each other, knife adjusting mechanism, and connections between said means and mechanism to establish correspondence between the adjustment of the knives and the relation between the mold and matrices.

In testimony whereof I affix my signature in presence of two witnesses.

THOMAS A. VERHOEVEN.
